(57) **CLAIM**

The ornamental design for a shoe sole, as shown and described.

DESCRIPTION

FIG. 1 is a bottom plan view of a shoe sole, showing my new design, shown in use as a part of a shoe.

FIG. 2 is a right side view of the shoe sole.

FIG. 3 is a left side view of the shoe sole.

FIG. 4 is a top plan view of the shoe sole.

FIG. 5 is front view of the shoe sole; and,

FIG. 6 is a back view of the shoe sole.

The upper elements shown in dotted line form no part of the invention. Shown is a shoe sole for a right shoe. Also claimed is a second embodiment of a sole for a left shoe wherein all Figures are mirror images of the Figures described above.
